CHANNEL CLOSING MACHINE

Leonard E. Proulx, Arlington, Mass., assignor to
United Shoe Machinery Corporation, Flemington, N. J., a corporation of New Jersey

Application January 15, 1944, Serial No. 518,384

6 Claims. (Cl. 12—29)

This invention relates to machines for laying the channel flaps of shoes and is herein illustrated and described as embodied in a machine provided with work-feeding means and also with an improved rotary flap-laying tool.

Inasmuch as the soles of shoes are not flat but are curved both transversely and longitudinally, it is important in channel-flap-laying machines to provide a tool capable of bearing with more or less uniform yielding pressure against the shoe, notwithstanding such irregularities of contour. This may be accomplished by including a resiliently supported yieldable element in the tool.

It is an object of this invention to provide an improved channel-flap-laying machine provided with a compact rotary tool having yieldable wiping members engageable with the shoe bottom. The flap-laying tool illustrated herein is provided with a plurality of wiping plates carried by a rotary tool body with their inner edges close to the axis of rotation and their outer edges further from said axis. As shown herein, and in accordance with a feature of the invention, these wipers are mounted in the tool body for yielding movement having an axial component under pressure of the work, and resilient means are provided to act upon said wipers in opposition to such yielding movement. In accordance with a further feature, the illustrated machine is provided with a driven roll engaging the upper of a shoe for feeding the shoe to the above-mentioned tool.

The invention further includes various features of construction and combinations of parts herein described and claimed, the advantages of which will be apparent to those skilled in the art from the accompanying description, reference being had to the accompanying drawings, in which

Fig. 1 is a side elevation of an illustrative machine embodying the invention;

Fig. 2 is a front elevation of the machine shown in Fig. 1;

Fig. 3 is an angular view of a channel-flap-lay- 45 tool with which the machine is provided;

Fig. 4 is a fragmentary sectional view of the channel-flap-laying tool;

Fig. 5 is a view in side elevation showing the operating instrumentalities of the machine in engagement with a shoe;

Fig. 6 is a side view of the tool, the outer portion being shown in diametrical section;

Fig. 7 is a section of the tool taken on the line VII—VII of Fig. 6;

Fig. 8 is an end view of the tool with the flange of the outer casing removed; and

Fig. 9 is a view similar to Fig. 4 of an alternative form of channel-flap-laying tool.

The operating instrumentalities of the machine consist of a channel-flap-laying tool 10 and a driven feed wheel 12. These members are supported by a machine frame 14 having a pair of upwardly extending parallel guide plates 16 and 18 (Fig. 2). The tool 10 has an upwardly extending stem or spindle 20 which is journaled for rotation in a bearing 22 having a bushing 24. In order to provide for heightwise adjustment of the tool 10 the bearing 22 is carried by a bracket 26 which in turn is pivotally mounted for swinging movement upon a pin 28 carried by the frame 14. In the illustrated construction the bearing 22 and the bracket 26 are integral. A coil compression spring 34 interposed between a lug 36 on the bracket 26 and an abutment 38 secured to the frame 14 bears against the bracket 26 to urge the tool downwardly. Such downward movement of the tool is limited by a stop screw 40 threaded through a lug 41 on the bracket 26 and engageable with an abutment 42 on the frame 14.

The tool 10 comprises a metal head 44 (Figs. 6 and 7) rigidly secured upon the lower end of the spindle 20 and having a cylindrical periphery. The lower end surface of the head 44, indicated by the reference character 46 (see also Figs. 3 and 4), is convex. Milled into the head 44 are twelve slots 48 (Fig. 6) each having a pair of plane parallel walls. These slots emerge in the periphery and also in the convex end surface 46 of the head; they do not, however, extend inwardly as far as the axis, but leave a central portion 50 (Fig. 7) surrounding the stem 20 to hold the head together. The plane of each slot is inclined to the axis of the tool, such inclination being equal for all the slots. The slots are spaced at equal angular intervals about the axis, and they are symmetrical with respect to the axis. Seated in each of the slots 48 is a flat brass wiping plate 52. These wiping plates are just enough thinner than the widths of the slots to provide sliding clearance. Each plate has an end 54 which extends beyond the end surface 46 of the head and which is rounded to follow the general convexity of the end surface. Furthermore, the end 54 of each plate is rounded transversely of its own thickness to avoid any sharp edge which might damage the work. Extending from each plate beyond the cylindrical periphery of the head 44 is a lug 56 which serves a purpose later to be described. Secured against the inner or upper

end face of the head 44 by screws 58, and closing the inner or upper ends of the slots 48, is a disk 60 of greater diameter than the head 44. Surrounding the head 44, and interposed between the lugs 56 and the marginal under surface of the disk 60, is a ring 64 of sponge rubber. Surrounding the rubber ring 64 and the disk 60 is a cylindrical casing or cover 66 which retains the wiping plates within the slots by preventing outward radial movement. The casing 66 has an inturned flange 68 which engages the lugs 56 to limit outward axial movement of the wiping plates. The lugs 56 are thus normally held against the flange 68 by the rubber ring 64. The cover 66 is secured to the disk 60 by screws 10 (Fig. 3). In order to insure registration of the screw holes in the disk and the casing, a dowel pin 72 extending radially from the disk 60 engages a notch formed in the casing. It is evident that when the casing 66 is thus secured in position on the head, the wiping plates 52 will normally be held in their outermost positions as shown in Fig. 4 but that they may yield by compression of the rubber ring 64.

The feed wheel 12 consists of a ring 74 (Fig. 5) composed of rubber and carried by a hub 73 which is mounted for rotation on a stud 75 having a stem 76 threaded into a carrier 78. The stud 75 has a head 79 for retaining the feed wheel against outward axial movement. In order to provide for adjustment of the feed wheel toward and from the locality at which the operation is to be performed, the carrier 78 (Fig. 1) is pivotally mounted for swinging movement about a shaft 80 journaled in the lower portion of the frame 14. The shaft 80, which may be driven from any suitable source of power, rotates freely with respect to the carrier 78. A coil tension spring 82 has one end secured to the carrier 78 and its other end anchored to a pin 84 extending across the open space between the upright guide plates 16 and 18. The spring 82, which urges the carrier outwardly or toward the left as seen in Fig. 1, maintains the carrier in a position of adjustment which is determined by the engagement of a lug 86 on the carrier with a stop 88 on a slide 90. Formed in the upright plate 16 is a horizontal guideway 92 in which the slide 90 may be secured in adjusted position by a clamping nut 94 threaded on the end of a stem 96 extending outwardly from the slide through a slot 98 in the guideway.

The tool 10 and the feed wheel 12 are driven from the drive shaft 80 which, in turn, may be driven from any suitable source of power. Secured upon the shaft 80 is a pulley 106 over which runs a belt 108 for the purpose of transmitting the drive of the shaft 80 to a pulley 110 carried by a shaft 112. An arm 114 extending upwardly from the bearing 22 carries a bearing 116 for the shaft 112. A bevel gear 118 secured upon an end of the shaft 112 engages a bevel gear 120 secured upon the upper end of the spindle 20 to drive the tool 10. For driving the feed roll 12, there is provided on the shaft 80 a worm gear 122 which meshes with the worm gear 124 on the lower end of a shaft 126 journaled in suitable bearings mounted in the carrier 78. A bevel gear 128 (see also Fig. 5) on the upper end of the shaft 126 meshes with a bevel gear 130 carried by a shaft 132 also journaled in the carrier 78. A bevel gear 134 on the opposite end of the shaft 132 meshes with a bevel gear 136 secured to the hub 73 to drive the feed wheel 12.

In the modified form of tool shown in Fig. 9,

the head 44 is similar to the head 44 already described except for being slightly longer axially. In place of the disk 60 is a thinner disk 138 having a depending peripheral flange 140 which surrounds the head 44 and supports the casing 66. The rubber ring 64 is omitted; its function is performed by individual coil compression springs 142, one for each wiping plate 52. Each spring 142 has its upper end abutting against the disk 138 and its lower end exerting a downward thrust against its associated wiping plate 52. Each spring surrounds a supporting stem 144 which extends upwardly from its associated wiping plate. The lugs 56 engage the flange 68 to limit outward movement of their wiping plates in the same way as in the form of head already described.

The operation of the machine is illustrated in Fig. 5. A shoe S is presented by hand to the flap-laying tool 10, with the upper of the shoe against the feed wheel 12. The purpose of the feed wheel is not only to impart a feeding movement to the shoe but also to maintain the shoe in engaged position relatively to the tool 10, with the channel flap or lip L in engagement with the wiping members 52. The work-engaging ends 54 of the wiping members are long enough to take care of variations, in the same shoe or in shoes of like size and style, in the distance between the channel lip L and the point of contact between the feed roll and the upper of the shoe. For the larger variations in this distance which are encountered in working upon shoes which differ widely in size or style, the slide 90 may be adjusted in its guideway. Changes in relative heightwise adjustment between the tool and the feed wheel may also be necessary; such changes are effected through the stop screw 40. Any irregularities of contour of the shoe bottom will be accommodated by the individual yielding of the wiping members 52. All that the operator has to do while thus holding the shoe is to permit the shoe to turn under the influence of the feed wheel while the wiping members progressively lay the channel flap.

Having described my invention, what I claim as new and desire to secure by Letters Patent of the United States is:

1. A channel-flap-laying tool comprising a rotary tool body, a plurality of wipers arranged annularly about the axis of the tool body and extending from an end face of the tool body for engagement with the work, said wipers being mounted in said tool body for yielding movement having an axial component under pressure of the work, and resilient means acting upon said wipers to oppose said yielding movement.
2. A channel-flap-laying tool comprising a rotary tool body, a plurality of wiping plates mounted in said tool body with provision for movement having a component along the axis of rotation, and resilient means acting upon said plates for yieldingly resisting such movement under pressure of the work.
3. A channel-flap-laying tool comprising a rotary tool body having a plurality of slots distributed around the axis of the tool body, a wiping plate slidable in each of said slots, and resilient means acting upon said plates for yieldingly resisting movement of the plates under pressure of the work in a direction having a component along the axis of rotation.
4. A channel-flap-laying tool comprising a rotary tool body having a plurality of slots distributed symmetrically around the axis of the

tool body, the planes of said slots making equal acute angles with said axis, a wiping plate slideable in each of said slots, and resilient means acting upon said plates for yieldingly resisting movement of the plates under pressure of the work in a direction having a component along said axis.

5. A channel-flap-laying tool comprising a rotary tool body, a plurality of wiping plates mounted in said tool body with provision for movement having a component in the direction of the axis of rotation, and a ring of rubber engage-

10 able with said plates to resist said movement under pressure of the work.

6. A channel-flap-laying tool comprising a rotary tool body, a plurality of wiping plates mounted in said tool body with provision for movement having a component in the direction of the axis of rotation, and means including a plurality of springs individually associated with said wiping plates for yieldably holding each wiping plate against such movement under pressure of the work.
